CLAIM

The ornamental design for a vehicle storage compartment cover for a convertible top, as shown and described.

DESCRIPTION

FIG. 1 is a top plan view of a vehicle storage compartment cover for a convertible top showing my new design;

FIG. 2 is a front elevational view thereof;

FIG. 3 is a rear elevational view thereof;

FIG. 4 is a side elevational view thereof, the opposite side being a mirror image of that shown; and,

FIG. 5 is a bottom plan view thereof.
